TWO-WAY SAFETY RELEASE FOR NEEDLE
DRIVE FOR BALERSJames H. Bornzin, Memphis, Tenn., assignor to
International Harvester Company, a corpora-
tion of New Jersey

Application August 19, 1949, Serial No. 111,207

4 Claims. (Cl. 100—20)

1

This invention relates to a new two-way safety release for needle drive for balers.

Hay balers, and particularly automatic hay balers, employ bale tying mechanisms which are very exacting in their operation and require numerous expensive parts. It is a principal object of this invention to eliminate the possibility of damage to the bale tying mechanisms.

An important object of this invention is the provision of means in a strand tying hay baler for a safety release in the wire carrying needle drive.

Another and further important object of this invention is to provide in a hay baler a strand carrying needle for encircling a strand about a formed bale and means in the needle drive for automatically releasing the drive should the needle become jammed or otherwise inoperable.

Another and still further important object of this invention is to supply a strand tying hay baler with yieldable safety release means capable of actuation during any portion of the strand encircling operation so that if the strand becomes kinked or otherwise fails to "pay" out during either an upward or downward movement of the strand carrying needle the drive will be automatically disconnected.

This invention is an improvement over the mechanism shown in the copending Patent 2,485,001 entitled "Wire Tying Baler" which issued October 19, 1949. In this copending patent a safety release means is employed in the needle drive but is only capable of actuation when the needle is progressing through its forward or upward stroke through the bale chamber. The present invention obviates this possible shortcoming and employs a novel release mechanism capable of drive disconnection in either direction of travel of the strand carrying needle.

A still further important object of this invention is to provide means in a safety release mechanism for driving elements in which the drive mechanism will automatically reengage during each cycle of operation of the drive and thereupon if the cause of the drive being initially separated is eliminated then drive may and will automatically resume.

Other and further important objects of this invention will become apparent from the disclosures in the following specification and accompanying drawings in which:

Fig. 1 is a side elevational view of a baler employing the safety release mechanism of this invention.

Fig. 2 is a sectional view taken on the line 2—2 of Fig. 1.

2

Fig. 3 is a side elevational view similar to that of Fig. 1 and showing the releasable mechanism in disengaged position during upward movement of the strand carrying needle.

Fig. 4 is a view partially in section of the safety release mechanism shown in drive disconnected position.

Fig. 5 is a side elevational view similar to Fig. 3 but with the safety release mechanism shown released from the other side as caused by a downward movement of the strand carrying needle as it pulls downwardly through the baling chamber.

As shown in the drawings, the reference numeral 10 indicates generally a bale forming chamber for an automatically operable hay baler. There are numerous baling machines of this type and hay is compressed as a rule by a reciprocating plunger. A strand 12 which may be either wire or twine is adapted to encircle the formed bale prior to its discharge from the baling chamber. As shown in Fig. 1, the wire tie strand 12 is carried upwardly into position through the baling chamber 10 by means of spaced arcuate strand carrying needles 14 having spaced guide rollers 16 and 18 at their upper ends. The source of strand is a container 20 positioned to one side of the bale chamber 10 and having a coil therein adapted to have one end thereof discharge through a downwardly extending tube 22 and thence around a guide roller 24 and upwardly through the bale chamber 10.

Hay to be baled enters the bale chamber 10 substantially at the position designated by the numeral 26. A fork feeding mechanism 28 is adapted to move the material from a receiving platform (not shown) into the bale chamber and thereupon a plunger, the forward end of which is shown at 30, compresses the hay against the vertical strand 32 extending upwardly from the guide roller 24 to the needle guide roller 18. As the needles 14 move upwardly through the bale chamber 10 they carry loops of strand consisting of the vertical portion 32 and a spaced vertical portion 34 joined by a connecting or bight portion 36. The portion 34 of the strand 12 includes the completed end of a compressed bale 38. A portion of the strand 40 corresponding to the vertical portion 32 has been extended about the top, the other end, and the bottom of the bale by reason of a "paying" out of the tie strand from the container 20 over the guide roller 24 and the needle guide rollers 16 and 18. Tying or twisting mechanism is thereupon employed on the strand portions 34 and 40 and the strand severed at the bight portion 36 so that the com-

55

pleted bale 38 may be discharged from the baling machine and remain compactly tied. This mechanism is described in detail in the copending patent of Paul Kane, mentioned above.

In order to complete the description of that portion of the baling machine pertinent to this invention it is pointed out that the bale chamber 10 is carried on a frame structure 42 which in turn is mounted on an axle 44 carried by spaced wheels, one of which is broken away to show the operating mechanisms. One of the wheel 46 is shown on the far side of the machine. Drive for the tie strand moving mechanism is taken from the shaft 48 which is driven by a power plant (not shown) forming a part of the baling machine, or drive for the shaft 48 may be received through a tractor power-take-off. An eccentric member 50 is attached to the shaft 48 by means by a key 52 and thus rotates with the shaft. The eccentric member 50 has a cam track 54 forming the outer periphery thereof. The cam track 54 is engaged by follower 56 which forms a part of a relatively long lever or arm 58 pivoted at 60 on a superstructure 62 of the framework 42. Thus, as the eccentric member 50 is rotated about the shaft 48 the arm 58 will swing back and forth in an oscillatory movement about the pivot 60. A lower depending end 64 of the arm 58 thus has movement through an arcuate path about pivot 60.

Reciprocal drive for the needle 14 is obtained through movement of this lower depending portion 64 of the arm 58. The needle 14 is provided with fixed angularly extending lever arms 66 fastened on a shaft 68 which carries the lower ends of the needles. The upper ends of the arms 66 are journaled in bearings 70 on the opposite sides of the bale forming chamber 10. The needles 14 and their unitary arms 66 are swung about their pivotal mountings 70 through a range beginning at the bottom of the bale chamber and passing upwardly therethrough to a position in which the needles project upwardly about the bale chamber 10 as indicated in Fig. 1. An arcuate guide track or shield 72 is carried on the frame structure 42 and tends to guide the needle in its travel beneath the bale chamber 10. Drive from the arm 58 to the needle structure and particularly the arm 66 is accomplished through a connecting link 74. The link 74 is pivotally mounted at 76 on the arm 66 and at its other end joins the arm 58 through the mechanism as shown in Fig. 2.

The connecting link 74 comprises a pair of spaced members 74^a and 74^b. Swingable members, links, or arms 78 and 80 are hingedly mounted at 82 on the depending portion 64 of the arm 58 and project downwardly and outwardly therefrom and thence downwardly in parallel relationship to a position adjacent the bottom of the depending arm 64 whereupon the side members 78 and 80 are inclined toward each other as shown at 83 and 84 and thereupon again extend downwardly in parallelism closely adjacent each other as shown at 86 and 88. Each of these portions 86 and 88 is provided with a transversely disposed aligned opening 90 and 92 respectively through which a shaft or pin 94 is adapted to pass. The shaft 94 is in the form of a bolt having a head 96 and adjustable nut means 98 at the opposite end thereof. Springs 100 and 102 are disposed between the member 86 and the nut 98 and the member 88 and the bolt head 96 respectively. These springs are substantially equal in strength and act to force the members 86 and 88 yieldably together.

The nut 98 is laterally adjustable along the spring holding shaft to permit a pretensioning of the coil springs. The arm 78 carries a bolt member 104 having a head 106 and a conical-shaped latch member 108 threadedly engaging the inner end thereof. The bolt 104 passes through the link arm 74^a and thus the arms 74^a and 78 become pivotally attached to the bolt member 104. The conical member 108 is adapted to project within a conical-shaped socket 110 in the lower end of the depending portion 64 of the swingable drive arm 58. The depending arm 64 is provided with wear plates 112 and 114 on opposite sides thereof for the purpose of reinforcing the edge strength of the conical socket 110 in one side thereof and a conical socket 116 in the other side thereof which is engaged by a conical member 118. The member 118 is mounted on a bolt 120 corresponding to the bolt 104 also having a head 122. The bolt 120 with its conical inner end 118 and its outer head 122 joins the arms 74^b and 80 as a pivotal unit.

Drive for the needles 14 is thus made possible through the yieldable linkage just described in Fig. 2, whereupon the reciprocal swinging movement of the arm 58 is imparted to the needle arms 66 by the connecting link 74. Throughout all ordinary operation of the baler the tie strand 12 is fed from the container 20 around the roller guide members and upwardly through the bale chamber by the needles 14. As long as the strand "pays" out freely from the container 20 and there is no other jamming of the needles 14, the springs 100 and 102 will maintain the conical members 108 and 118 in engaging position with the conical receiving sockets in the lower end of the depending portion 64 of the drive arm 58 and thus drive through this mechanism will remain in operation.

In the event there is a tangling of the strand and an excessive force is applied to the needles 14 during the movement of the needles upwardly through the bale chamber 10 as shown in Fig. 3, the drive arm 58 may swing away from the conical projection members 108 and 118 by reason of the arms 78 and 80 spreading against the action of the springs 100 and 102, thus causing a disconnecting of the drive from the arm 58 to the needles 14. The arm 58 is permitted to make its arcuate swinging movement about its pivotal mounting 60 while the arms 78 and 80 carrying the release mechanism freely swing about their pivotal attachment 82 on the arm 58. In the event the wire tangle is corrected or the other reason for jamming of the needles is removed, then upon the succeeding cycle or swinging movement of the arm 58 the arms 78 and 80 will be spread apart upon each cycle movement of the arm 58 and the male conical members 108 and 118 will reengage the conical-shaped sockets 110 and 116 in the arm 58, whereupon drive to the needles will be reengaged and operation of the baler resumed. However, if the reason for jamming or breaking of the needle drive is not corrected during a cycle swing movement of the arm 58, the operation of the releasing and reengaging will be continued without any driving movement of the needles 14. The spreading of the arms 78 and 80 against the action of the springs 100 and 102 upon a predetermined tension of the strand or any obstruction such as a foreign object in the path of the needles is shown in Fig. 4.

Fig. 5 shows the releasing mechanism of Figs. 2 and 4 in drive disconnecting position during the

withdrawing portion of the needle stroke. The symmetrical conical release mechanism is operable in either direction and thus release of needle drive is accomplished at any time the needle might become jammed. Successive cycles of swinging movement of the arm 58 will similarly cause a reengagement of the drive and a resuming of needle movement after the jamming reason has been removed. However, similarly to the position of the needle in Fig. 3, if the needle is still jammed upon a successive swinging movement of the arm 58, it will again and successively continue to disconnect the drive until the cause of jamming is corrected.

Obviously when the operator of this baling machine hears the snap-acting of the drive release mechanism operating he will immediately know that something is causing the needles to jam and if it does not immediately correct itself he will be sufficiently warned to turn off the source of power and correct the difficulty as necessary. Serious damage to the needles, breaking of the strand, or damage to the adjacent elements is prevented with the safety device of this invention employed thereon.

Numerous details of construction may be varied throughout a wide range without departing from the principles disclosed herein and I therefore do not propose limiting the patent granted hereon otherwise than as necessitated by the appended claims.

What is claimed is:

1. In a baling mechanism having a bale chamber with an associated frame structure and reciprocating means for compressing hay in said chamber, a bale tie-forming means including means for holding a supply of tie-strand, a lever arm mounted on the bale chamber for oscillatory motion, an arcuate tie-strand carrying needle mounted on an end of said arm in a position to be moved into and through the bale chamber by oscillation of the arm, means for guiding a tie-strand from said supply to said needle, driving mechanism for said needle including a lever mounted for oscillation on the frame structure associated with the bale chamber, a swingable link pivoted to said lever, a member pivotally connected to said link adjacent one end and pivotally secured to the lever at the other end for oscillating said lever arm, a spring-loaded latch member carried by said member and said swingable link, said latch member being releasably engageable with a portion of the lever whereby when a predetermined tension is reached on the tie-strand, the latch will release thereby preventing breaking of the tie-strand and damage to the mechanism, means carrying the spring-loaded latch member comprising said swingable link having spaced arm portions, yieldable means normally holding said arm portions together, said member having spaced arm portions, and means joining one of each of the arm portions of the swingable link and the member, a projecting portion on each of said joining means, said lever having socket means for engagement by said projecting portions, whereby needle drive continues as long as the projecting portions engage the socket means and ceases when the projecting portions ride out of the socket means.

2. A device as set forth in claim 1 in which the projecting portions are conical in shape and the socket means are similarly conical in shape whereby the riding of the projecting portions out of the sockets is assured regardless of which direction the needle is traveling when the tie strand jams.

3. In a baling mechanism having a bale chamber with an associated frame structure and reciprocating means for compressing hay in said chamber, a bale tie-forming means including means for holding a supply of tie-strand, a lever arm mounted on the bale chamber for oscillatory motion, an arcuate tie-strand carrying needle mounted on the end of said arm in a position to be moved into and through the bale chamber by oscillation of the arm, means for guiding a tie-strand from said supply to said needle, driving mechanism for said needle including a lever mounted for oscillation on the frame structure associated with the bale chamber, a swingable link pivoted to said lever, a member pivotally connected to said link adjacent one end and pivotally secured to the lever at the other end for oscillating said lever arm, a spring-loaded latch member carried by said member and said swingable link, said latch member being releasably engageable with a portion of the lever whereby when a predetermined tension is reached on the tie-strand, the latch will release thereby preventing breaking of the tie-strand and damage to the mechanism, means carrying the spring-loaded latch member comprising said swingable link having spaced arm portions, yieldable means normally holding said arm portions together, said member having spaced arm portions, means joining one of each of the arm portions of the swingable link and the member, a projecting portion on each of said joining means, said lever having socket means for engagement by said projecting portions, whereby needle drive continues as long as the projecting portions engage the socket means and ceases when the projecting portions ride out of the socket means, said yieldable means including said swingable link spaced arm portions having aligned openings, shaft means passing loosely through said aligned openings, end means for said shaft, and coil springs disposed between each of said arm portions and said shaft end means, whereby the coil springs urge the arm portions together.

4. A device as set forth in claim 3 in which at least one of said shaft end means is adjustably secured to said shaft to permit a pre-tensioning of the coil springs.
